UNITED STATES PATENT OFFICE

2,006,992

REFRIGERATING APPARATUS

Frank T. Grothouse, Fort Wayne, Ind., assignor
to General Electric Company, a corporation of
New York

Application April 6, 1934, Serial No. 719,355

8 Claims. (Cl. 62—116)

My invention relates to refrigerating apparatus.

An object of my invention is to provide a compact arrangement for mounting the parts of the refrigerating apparatus within an enclosing casting and for dissipating heat generated therein.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a perspective view partly broken away of refrigerating apparatus embodying my invention; Fig. 2 is a perspective view of the mounting frame for supporting the motor and compressor; and Fig. 3 is a perspective view partly broken away of the heat exchanger.

Referring to the drawing, the refrigerating apparatus is shown as a part of a room cooler having an outer casing 1. The refrigerating apparatus is enclosed within a casing 1a formed between one end of the casing 1 and a partition 2 extending across the casing. The refrigerating apparatus includes a compressor 12 and a motor 13 which are mounted on a supporting frame within the casing. The supporting or mounting frame comprises a base 3 to which are secured vertical plates 4 and 5 welded thereto at 6 and 7. A horizontal plate 8 is attached to the upper ends of the vertical plates 4 and 5 and is supported thereby above and spaced from the base plate 3. Reinforcing members 9 are welded at the junctions between the horizontal and vertical plates and assist in fastening the plates together to form a rigid construction. The vertical plate 4 is spaced from the end of casing 1a and has an opening 10 therein through which air may circulate from the end of the casing into the interior of the mounting frame. The vertical plate 5 is arranged against the partition 2. The horizontal plate 8 has an opening 18 therein adjacent the end plate 5, and a heat-exchange device 19 which is preferably a radiator through which cooling water may be circulated, is supported at the opening 18. The mounting frame extends substantially across the casing 1a and defines an air passage within the casing extending between the horizontal plate 8, which acts as a baffle, and the base of the casing, and communicates with the casing 1a at either end through openings 10 and 18. The mounting frame is secured to the base of casing 1a by bolts 11.

A compressor 12 is mounted on the horizontal

plate 8 and is driven by an electric motor 13 through a drive which includes pulleys 14 and 15, mounted respectively on the compressor and motor, and belts 16. The motor 13 is supported at the bottom of casing 1a on the plate 3 by vertically adjustable bolts 17. The vertical position of the motor 13 may be varied by means of the bolts 17 to vary the tension of belt 16. A fan 20 mounted on the shaft of motor 13 within the opening 10 circulates air from opening 10, through the passage between baffle 8 and the casing 1a, over the motor 13, through the heat-exchange device 19 arranged in opening 18, and over the compressor 12. A water-cooled condenser 22, comprising concentric tubes, is arranged on the walls of the casing 1a and surrounds the compressor 12. The refrigerant to be condensed flows to one of the concentric tubes of condenser 22, through tube 23, cooled by cooling water flowing in the other concentric tube, and flows from the condenser 20 to a receiver 24 through tube 25.

The expanded refrigerant is conducted from the evaporator by pipe 32 to one of the concentric tubes of a heat exchanger 33 arranged at the back of the casing 1a. The other of the concentric tubes contains liquid refrigerant which is conducted from the receiver 24 by the pipe 34 to the heat exchanger 33 and is conducted from the heat exchanger to the evaporator by pipe 35. A filter chamber 36 is arranged in the pipe 35 to remove foreign matter from the refrigerant. By this arrangement the expanded refrigerant is used to cool the liquid refrigerant and the efficiency of the refrigerating system is improved. From the heat exchanger 33 the expanded refrigerant is led to the compressor by pipe 37. The compressed refrigerant flows from the compressor 12 to the condenser 22 by pipe 23 and is condensed in the condenser 22. The liquid refrigerant flows from the condenser 22 to the receiver 24 by way of pipe 25. In the operation of the refrigerating apparatus, the compressed refrigerating fluid is cooled by water flowing through the condenser 22 and the water jacket in the compressor 12, and also further cooled by the expanded refrigerant flowing in heat exchanger 33.

The cooling water is conducted within the casing by pipe 26 through a control valve 27 to the heat exchange device 19. From the heat exchange device 19, the cooling water is conducted to the condenser 22 by pipe 28. The cooling water leaves the condenser by pipe 30 and flows to the water jacket in the compressor and is con-

ducted from the compressor to a point outside the casing by pipe 31.

Heat is removed from the air within the casing 1a by heat exchange device 19, through which

5 the cooling water circulates. By this arrangement it is possible to arrange the refrigerating apparatus compactly within an enclosing casing so as to dissipate heat from the apparatus and to maintain the air within the casing at a temperature low enough so that the electric motor 13

10 will not overheat.

15 Although I have shown a particular embodiment of my invention, I do not desire to be limited to the construction described, and I intend in the appended claims to cover all modifications which do not depart from the spirit and scope of my invention.

20 What I claim as new and desire to secure by Letters Patent of the United States, is:

25 1. A refrigerating apparatus comprising a closed casing, means including a plate arranged within said casing and spaced therefrom for defining an air passage between said plate and said casing, a motor element and a compressor element driven thereby arranged on opposite sides of said plate, one of said elements being supported by said plate, means including a fan for circulating air around said plate and over said motor and said compressor, and means including

30 a heat exchange device arranged in the path of air circulating over said motor and said compressor for cooling the circulated air.

35 2. A refrigerating apparatus comprising a closed casing, means including a plate having an opening therein arranged within said casing and spaced therefrom for defining an air passage between said plate and said casing communicating at either end with said casing, a motor element and a compressor element driven thereby arranged on opposite sides of said plate, one of said elements being supported by said plate, means including a fan for circulating air around said plate through said opening and over said motor and said compressor, and means including

40 a heat exchange device arranged at said opening for cooling the circulated air.

45 3. A refrigerating apparatus comprising a closed casing, means including a horizontally disposed baffle for forming an air passage between said baffle and said casing communicating at either end with said casing, a motor mounted below said baffle, a compressor mounted on and above said baffle, means including a fan for circulating air around said baffle and over said motor and said compressor, and means including a heat exchange device arranged in the path of the circulated air for cooling the circulated air.

50 4. A refrigerating apparatus comprising a closed casing, means including a horizontally disposed baffle for forming an air passage between said baffle and said casing communicating at either end with said casing, a motor mounted below said baffle, a compressor mounted on and above said baffle, means including a fan for circulating air around said baffle and over said motor and said compressor, a condenser arranged about the walls of said casing, means including a heat

5 exchange device arranged in the path of the circulating air for cooling the circulated air, and means for circulating cooling water through said heat exchange device and said condenser.

10 5. A refrigerating apparatus comprising a closed casing, means including a horizontally disposed baffle for forming an air passage between said baffle and said casing communicating at either end with said casing, a motor mounted below said baffle, a compressor mounted on and above said baffle, means including a fan for circulating air around said baffle and over said motor and said compressor, a condenser arranged on the walls of said casing and surrounding said compressor, means including a heat exchange device arranged in the path of the circulating air for cooling the circulated air, and means for circulating cooling water through said heat exchange device and said condenser.

15 6. A refrigerating apparatus comprising a closed casing, a motor mounted at the bottom of said casing, a mounting frame having a horizontal plate arranged above said motor, a compressor mounted on said plate, said plate defining a passage communicating at either end with said casing for circulating air over said motor, means including a fan for circulating air around said plate and over said motor and said compressor, and means including a heat exchange device arranged in the path of the circulating air for cooling the circulated air.

20 7. A refrigerating apparatus comprising a closed casing, a mounting frame within said casing including a vertical end plate spaced from said casing and having an opening therein and a horizontal plate spaced from said casing and supported by said end plate, said horizontal plate opening therein, a motor and a compressor arranged on opposite sides of said horizontal plate, means including a fan arranged at the opening of said end plate for circulating air through the opening in said end plate and around said horizontal plate and over said motor and said compressor, and means including a heat exchange device arranged at the opening in said horizontal plate for cooling the circulated air.

25 8. A refrigerating apparatus comprising a closed casing, a mounting frame within said casing including a vertical end plate spaced from said casing having an opening therein and a horizontal plate spaced from said casing and supported by said end plate, said horizontal plate having an opening therein, a motor and a compressor arranged on opposite sides of said horizontal plate, means including a fan arranged at the opening in said end plate for circulating air through the opening in said end plate and around said horizontal plate and over said motor and said compressor, means including a heat exchange device arranged at the opening in said horizontal plate for cooling the circulated air, a condenser arranged on the walls of said casing and surrounding said compressor, and means for circulating cooling water through said heat exchange device and said condenser.
